UNITED STATES PATENT OFFICE.

JOHN CARVER, OF DETROIT, MICHIGAN.

HINGE FOR AUTOMOBILE-HOODS.

1,180,254.

Specification of Letters Patent. Patented Apr. 18, 1916.

Application filed June 23, 1915. Serial No. 35,794.

To all whom it may concern:

Be it known that I, JOHN CARVER, a subject of the Kingdom of Great Britain, residing at Detroit, in the county of Wayne, State of Michigan, have invented certain new and useful Improvements in Hinges for Automobile-Hoods; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to hinges especially designed and adapted for use in connection with automobile hoods, and it consists in the novel features of construction herein-after more fully set forth and claimed.

The invention has for its object the provision of a comparatively simple, inexpensive and efficient hinge construction for pivotally mounting the hood over the motor of an automobile, in which the arrangement is such as to provide independent pivotal connections for each of the two halves comprising the hood to render them self-locking and separately detachable so as to facilitate the handling in their removal and replacement, and wherein the construction is such as to conceal the hinge connections within the hood, and also to effect a weather-tight closure between the adjoining edges of the two parts of the hood in a manner to present a comparatively smooth finish on the exterior surface thereof.

The preferred form of embodiment of the present invention by which the above object is attained is illustrated in the accompanying drawings, in which,

Figure 1 is a central longitudinal sectional view through the hood and a portion of the radiator and dash of the car, between which said hood is mounted. Fig. 2 is a longitudinal sectional view through one of the hinged sides of the hood, as on dashed line 2--2 of Fig. 3. Fig. 3 is a central cross-sectional view through the body of the hood, showing the relation of the two halves to each other and engaged at their hinged edges with the under face of an overlapping weather strip, as in the closed position of the hood. Fig. 4 is a detail view in perspective of the double

hinge supporting bracket. Fig. 5 is a fragmentary transverse sectional view through one of the supporting brackets of the hinged hood sections on dashed line 5--5 of Fig. 1, and indicating by dotted lines one of the hood sections in an upturned position.

Referring to the parts of the device by the characters of reference marked on the several views of the drawings, 1 designates a portion of the cowl of the body of the vehicle containing the dash 2, and 3 indicates a portion of the radiator, between which and the dash the hood is mounted. The hood consists of two upper oppositely inclined sections 4, to the lower edges of which vertical side sections 5 are commonly hinged as at 6 to fold inwardly upon the upper sections, respectively. These hood sections are supported at opposite ends in the usual way upon the laterally projecting ledges 7 and 8 formed respectively on the opposed faces of the cowl 1 and radiator 3.

The hood sections are hinged to swing upwardly independently of each other upon pivots at opposite ends journaled in supporting brackets secured respectively to the dash 2 and radiator 3. Each of these brackets, of which there are two, comprises a base plate 9, extending into the body of which is a vertical depression having laterally projecting oppositely inclined ribs forming under-cut side walls 10, which are connected at the bottom of the depression by a horizontal rib 11, from the upper face of which a binding post 12 extends vertically and centrally in line with the base plate 9 and divides said depression into two vertical openings 13. The upper edge of the base plate 9 is formed at opposite ends with laterally projecting flanges 14 recessed in their upper faces and joined at their inner ends with the side walls 10 by journal bearing bosses 15. Each of these bosses has a bore 16 extending therethrough, with which a relatively narrow radial slot 17 communicates vertically through the upper wall thereof, as clearly shown in Fig. 4. These brackets are disposed in reversely opposed relation upon the inner faces, respectively, of the dash and radiator, the ledges 7 and 8 of which are cut away between the flanges of the brackets, one of which is secured through its flanges 14 to the ledge 7 of the cowl by rivets 18 through apertures 19 therein, and also to the face of the dash 110

by screws or rivets 20 through apertures 21 in the base plate 9. The other of said brackets is correspondingly secured to the ledge 8 and the meeting face of the radiator 3 in similar manner, as shown in Figs. 2 and 5. The brackets thus disposed are connected together by means of a tie-rod 22 which is secured at one end in an aperture 23 in the upper end of the binding post 12 10 of the bracket on the radiator, and is screw-threaded at its opposite end and extended through the aperture 23 of the post 12 of the dash bracket, being secured through said dash by jam nuts 24 and 25 on said rod between 15 which said post and dash are confined, respectively. Mounted upon this rod is a metal weather strip 27, folded upon itself in the form of a T, the stem of which is formed tubular at its lower end and embeds 20 said rod upon which it is positioned with the cross member lying in a horizontal plane and abutting at opposite ends against the inner faces of the cowl and radiator respectively. The tubular portion and stem 25 of this strip is cut away at opposite ends to accommodate the binding posts carrying the tie-rod. (See Fig. 1.)

The metal at the upper edge of each of the hood sections 4 is folded inwardly upon 30 itself and is then rolled in the form of a sleeve or tube 28, which extends longitudinally of the hood upon the under side thereof at a point some distance back of its upper folded edge. The ends of the tubes 28 are 35 cut short of the ends of the hood sections and abut against the inner faces of the journal bearing bosses 15, with which they lie in registering alinement. (See Fig. 2). Inserted in the ends of these tubes are hinge 40 pintles 29, the ends 30 of which project beyond the ends of the tubes and are formed cam-shape by flattening the surfaces upon opposite sides sufficiently to permit the reduced or minor diameters to pass through 45 the slots 17 and enter the pintles in the bores 16 of the bosses 15, wherein the major diameters of said pintles when rotated will be caused to abridge said slots and prevent disengagement therethrough except when 50 turned to bring their minor diameters into registering alinement therewith. In this way each hood section is provided with a self-locking detachable hinged connection upon which it may be swung independently 55 of the other. By arranging the pivotal axes eccentric to the hinged edges of the hood sections, these overhanging edges are caused to swing vertically in the arc of circles toward and from the cross member of the 60 weather strip 27, which movement is accommodated at the ends of the sections by the openings 13 of the hinge brackets, and when in the down-folded position the adjacent edges of the hood sections are caused 65 to overlap and engage the under face of the

weather strip, which effects a water-tight closure of the joint between said sections, as shown in Figs. 3 and 5. In this position the major diameters of the pintles lie transversely of the slots 17 of the bosses 15 and 70 snugly filling the bores therein prevent disengagement therewith. The minor diameters of the pintles are so positioned with the plane of the hood sections that when a section is raised to the vertical dotted position 75 shown in Fig. 5, its overhanging hinged edge will engage at opposite ends with the inner face of the walls 10 of the hinge brackets, which serve as stops to limit the swinging movement of the section and position the minor diameters of the pintles in 80 registering alinement with the slots of the hinge bosses, through which said pintles may be passed to disengage the hinge connection when desirous of removing the section, by lifting upwardly thereon.

Having thus fully set forth my invention, what I claim as new, and desire to secure by Letters Patent, is:

1. An automobile hood hinge comprising 90 hood sections having hinge pintles, a pair of brackets for the hood sections, each bracket having a pair of hinge bearings spaced apart thereon and adapted to receive the hinge pintles of the hood sections, and 95 a tie strip connected at opposite ends with said brackets and overlapping said hood sections.

2. An automobile hood hinge comprising 100 a pair of hinge brackets adapted for attachment respectively to the dash and radiator of the vehicle, each bracket having a pair of hinge bearings spaced apart thereon and formed with radial slots therein, hood sections each carrying hinge pintles formed 105 with minor diameters for registering with said slots and major diameters for engagement within said bearings, and a tie strip secured at opposite ends to said brackets.

3. In a hood for automobiles, a pair of 110 hinge brackets for the hood sections, each having a pair of tubular hinge bearings spaced apart thereon, hood sections having hinge pintles for pivotal engagement with said bearings, and a T-shaped weather strip 115 connected with said brackets and interposed between said sections in overlapping relation therewith.

4. In a hood for automobiles, a pair of 120 hinge brackets adapted for attachment, respectively, to the dash and radiator of the vehicle, each bracket having a pair of tubular hinge bearings spaced apart thereon and provided with radial slots extending there-through, hood sections spaced apart and carrying near their adjacent edges hinge 125 pintles formed with minor diameters for registering with said slots and major diameters for reception within said bearings, a weather strip secured at opposite ends to 130

said brackets and overlapping the adjacent edges of said sections upon the upper faces thereof.

5. In a hood for automobiles, a pair of hinge brackets adapted for attachment, respectively, to the dash and radiator of the vehicle, each bracket having a pair of tubular bearings spaced apart thereon and provided with radial slots extending there-
10 through, hood sections spaced apart and having sleeves formed on their under faces near their adjacent edges, hinge pintles mounted in the ends of said sleeves and having their ends formed with minor diameters
15 for registering with said slots and major diameters for reception in said bearings, a

tie-rod connected at opposite ends with said brackets, and a weather strip mounted on said rod and overlapping the adjacent edges of said hood sections upon the upper faces 20 thereof.

6. In a hood for automobiles, a pair of hood sections disposed in opposed adjacent relation and hinged at opposite ends, respectively, to the dash and radiator of the 25 vehicle, and a weather strip secured at opposite ends, respectively, to said dash and radiator and overlapping the adjacent edges of said hood sections.

In testimony whereof, I have signed this 30 specification.

JOHN CARVER.
